UNITED STATES PATENT OFFICE.

JAMES STRANG, OF NEW YORK, N. Y.

LOOSE-LEAF BINDER.

No. 852,084.

Specification of Letters Patent.

Patented April 30, 1907.

Application filed January 21, 1907. Serial No. 353,174.

To all whom it may concern:

Be it known that I, JAMES STRANG, a citizen of the United States, residing in the borough of Brooklyn, city of New York, county of Kings, and State of New York, have invented certain new and useful Improvements in Loose-Leaf Binders, of which the following is a specification..

My improvements relate to the class of binders designed for the protection of "loose" leaves or signatures adapted for use in the ordinary type-writing machine—the object being to afford a comparatively simple construction and arrangement of parts in which provision is made for inserting or removing sheets at either the right or left sides of the back in which the operation of locking or unlocking the sides of the binder for the insertion or removal of sheets is expedited and rendered more convenient; and in which provision is made for rendering the binding permanent as hereinafter described and claimed specifically.

In the accompanying drawings, Figure 1, is an elevation of the parts adjoining the joint of the left hand cover with the sheet bars locked in position; Fig. 2. is a similar view with the bolt slide withdrawn from the lock tube and shown in elevation in Fig. 3; Fig. 4, is an end view upon an enlarged scale of the back portion of the binder, closed; Figs. 5 and 6, are respectively sections taken upon plane of lines 5—5— and 6—6— Fig. 1, on the same scale as Fig. 4; Fig. 7, is a central longitudinal section of the left hand lock tube; Fig. 8, is an elevation of the inner side of the back of the binder, the leaves being omitted and the sheet bars being locked in position; Fig. 9, is a similar view showing the sheet bars released from the left hand lock tube; Figs. 10 and 11, are sections upon an enlarged scale of one end of one of the lock tubes and of one of the bolt slides showing more clearly the means for permanently locking the slide within the tube; Figs. 12 and 13, are elevations in detail of one of the sheet bars; Fig. 14, is a section taken upon plane of line 14—14— Fig. 8.

C, C, represent the usual side boards or covers, united to and articulating upon the back B, at the joints b, b, in a manner well known in the art. Each cover C by preference consists of an outer sheet c, united to the back B, at the joint b, of an intermediate

sheet c', and of an inner sheet c'', said sheets being formed of card board or other suitable material in the usual manner. Interposed between the inner edges of the sheets c' and c'', is a metallic plate M, the general outline of which is shown in dotted lines in Figs. 1 and 2, and shown in cross section in Fig. 5. This plate M is formed with overlapping tongues m, m, which pass through the intermediate sheet c', and are doubled over thereon and between it and the outer sheet c, of the cover C as shown in Fig. 6,—the main object of this construction being to insure a substantial, rigid foundation and support for the lock tube m'. This lock tube m', is formed by doubling over the edge of the plate M which is to protrude from the inner edge of the cover when incorporated therewith,—the tube consists of a flat channel having parallel sides between which the bolt slide S, fits snugly. It is to be noted particularly in this connection that the above described construction is duplicated on each cover, and that each flat lock tube or channel protrudes from its cover in the same general plane as the cover itself. A back of relatively small or normal size and shape may thus be used as compared with other binders of this class, since the lock tubes m', occupy the side concavities b', b', of the back when the binder is closed, as will be seen by reference to Figs. 4, 5 and 6, thus economizing space and improving the appearance of the binder as a whole, since an ordinary book or ledger back may be used as shown in the drawings in contradistinction to the box backs of special construction usually resorted to in devices of this character. This is a feature of importance where the binding is eventually to be rendered permanent, as hereinafter set forth, since the device then constitutes, to all intents and purposes, a simple book of reference of ordinary shape and appearance.

Any desired number of sheet bars D may be used,—three being shown in the drawings, the lock tubes each being formed with a corresponding number of notches or recesses m², m², for the reception of the ends of the said sheet bars D, said ends being formed with bolt holes d, for the reception of the bolt tongues s', s², s³, on the bolt slide S. The sheet bolts D are curved slightly to conform somewhat to the curvature of the back B,

and are passed through the usual rectangular perforations p , in the paper sheets or signatures P .

I am aware that a bolt slide of somewhat similar construction to those herein used in conjunction with my right and left hand lock tubes is shown in Letters Patent No. 789,185 dated May 9th, 1905, and I do not seek to cover such construction broadly, the distinguishing feature in the present case consisting in making the bolt tongues s' , s^2 , s^3 , successively of less length, so that the first s' , will first engage the bolt hole d , in the first bar D , the second bolt tongue s^2 , next entering the bolt hole d , in the second sheet bar D , and so on. That is to say, the sheet bars are locked independently and successively. This is an important feature in actual use since it is a comparatively difficult and tedious operation to lock all the bars D simultaneously owing to the difficulty of setting and maintaining them in perfect alinement, whereas by my improved construction only one sheet bar has to be attended to at a time, a comparatively easy and simple task which may be accomplished without the exercise of much skill or patience. Furthermore, I use one of my special form of bolt slides S in conjunction with each of my flat lock tubes, so that sheets P may be inserted or removed with equal facility from either side of the binder. Thus sheets removed from the front or left hand side may be type-written and then replaced in the binder on the rear or right hand side of the binder, so that the pages will be compiled successively in a convenient and consistent manner, without the necessity of removing or re-arranging the pages after they have been type-written and filed. It further enables me to place on the market a full book, *i. e.*, one having the maximum number of sheets or signatures whereas heretofore, so far as I am aware, such binders have been accessible for the insertion, or removal of sheets on one side only, and have been built up by the addition of sheets independently stored, which is an objectionable feature in many respects, especially since it renders the binder dependent on an independently stored supply of loose sheets. In fact, in so far as my device is concerned the term "loose" sheets would hardly apply since the "book" is complete in itself, and the sheets are simply removable and interchangeable until such time as the book is completed and permanently locked. This I believe to be a distinguishing feature of my invention and one that renders it of practical importance over the prior state of the art in a commercial sense.

Each bolt slide S is formed with a hole or recess s^4 coinciding in position, when the slide is fully inserted in the tube m' , with a tongue m^3 , cut in one side of said flat tube m' .

When the book is complete this tongue is

forced into the hole s^4 , in the slide S , as will be understood particularly by reference to Figs. 10 and 11. Under ordinary conditions of use the tongue m^3 , is flat and even with the side wall out of which it is formed as in Fig. 10. It will be seen by reference to Fig. 11, that the depression or upsetting of the tongue m^3 , effectually and positively locks the slide S against longitudinal movement in either direction.

The outer end of each bolt slide S is formed with a lateral offset or shoulder s^5 , to facilitate the manipulation of the slide before it is locked permanently in position as above, and thereafter to act as a guard to prevent tampering with the tongue m^3 , after it is forced into the hole s^4 , as will be understood by reference to Fig. 11. That is to say, the lateral shoulder s^5 , projecting on the side on which said tongue m^3 , is situated prevents the insertion of any cutting tool or other implement whereby said tongue could be cut or otherwise be tampered with.

What I claim as my invention and desire to secure by Letters Patent is,

1. In a binder of the character described, the combination with the covers and perforated sheets, of a lock tube attached to a cover and formed with recesses for the reception of the ends or sheet bars, said sheet bars passing through said perforated sheets and formed with end perforations, and a bolt slide in said flat lock tube, said bolt slide being formed with bolt tongues arranged to successively engage with the bolt holes in sheet bars, for the purpose described.

2. In a binder of the character designated, the combination with the back and covers and with the perforated sheets, of a plurality of sheet bars passing through said perforated sheets each bar being formed with a bolt hole at each end, two flat lock tubes one attached to and projecting from each of the covers in the same general plane as that of the cover, each of said lock tubes being formed with recesses for the reception of the ends of the sheet bars and with a depressible tongue on one side wall, and two bolt slides, one in each of said flat lock tubes, said slides being each formed with bolt tongues for engagement with the bolt holes in the sheet bars and a slot or depression communicating with the depressible tongue in the side of the lock tube in which it is inserted, whereby the sheets may be removed from one side of the binder and replaced at the other side thereof, and whereby when the book is completed, the bolt slides may be permanently locked in position in the lock tubes for the purpose described.

3. In a binder of the character designated, the combination with the back and covers and with the perforated sheets, of a plurality of sheet bars passing through said perforated sheets, each bar being formed with a bolt

hole at each end, two flat lock tubes one attached to and projecting from each of the covers in the same general plane as that of the cover, each of said lock tubes being
5 formed with recesses for the reception of the ends of the sheet bars, and two bolt slides one in each of said flat lock tubes, each of said slides being formed with bolt tongues ar- | ranged to engage successively one in advance of the other, the bolt holes in the sheet bars, to for the purpose described.

JAMES STRANG.
